UNITED STATES PATENT OFFICE.

ERWIN M. JENNINGS AND CHARLES F. MOSMAN, OF BRIDGEPORT,
CONNECTICUT.

DESIGN FOR A CLOCK-CASE.

SPECIFICATION forming part of Design No. 30,984, dated June 13, 1899.

Application filed May 17, 1899. Serial No. 717,221. Term of patent 7 years.

To all whom it may concern:

Be it known that we, ERWIN M. JENNINGS and CHARLES F. MOSMAN, citizens of the United States, and residents of Bridgeport, in the county of Fairfield and State of Connecticut, have invented and produced a new and original Design for Clock-Cases, of which the following is a specification, reference being had to the accompanying drawings, forming part thereof.

Figure 1 is a front view of a clock-case embodying our new design. Fig. 2 is a side view of the same.

As shown in the drawings, the leading or material features of our design consist in a cylindrical portion comprising plain and beaded rings *a* and *b*, encircling the opening *c* for the clock-movement. These rings are surrounded by a series of irregular scroll and leaf ornamentations *d* and *e* of French rococo style, together with a lattice panel *f* at the base. The top portion of the case is surmounted by a representation of a shell *g*, in

the concave portion of which is seated a cupid *h*. The external cylindrical portions of the rear and front of the case contain a series of convex ribs *i*, and the case as a whole is supported on three graceful legs *j*, which are ornamented in scroll and leaf effect in harmony with the main body of the clock.

It is obvious that this design is also applicable to other uses than that herein mentioned.

Having thus described our invention, what we claim, and desire to secure by Letters Patent, is—

The design for a clock-case, as herein shown and described.

Signed at Bridgeport, Fairfield county, Connecticut, this 13th day of May, 1899.

ERWIN M. JENNINGS.
CHARLES F. MOSMAN.
